DESIGN FOR A FOAM SCRAPER HOLDER

Frank Farrell, New York, N. Y., assignor to Jacob Ruppert, New York, N. Y., a corporation of New York

Application June 7, 1947, Serial No. 139,508

Term of patent 14 years

(Cl. D2—3)

To all whom it may concern:

Be it known that I, Frank Farrell, a citizen of the United States, residing at New York city, in the county of New York and State of New York, have invented a new, original, and ornamental Design for a Foam Scraper Holder, of which the following is a specification, reference being had to the accompanying drawing, forming part thereof.

Fig. 1 is a perspective view of a foam scraper holder, showing my new design;

Fig. 2 is a section taken on line 2—2 of Fig. 3;

Fig. 3 is a side view; and

Fig. 4 is a front view thereof.

The dominant features of my design reside in the portions shown in full lines.

I claim:

The ornamental design for a foam scraper holder, substantially as shown and described.

FRANK FARRELL.
